DOUBLE-CLIP CLOTHES PIN

Veronica P. Murinka, Riverside, Calif.

Application April 23, 1956, Serial No. 41,170

Term of patent 14 years

(Cl. D17—6)

FIG. 2

FIG. 3

FIG. 4

FIG. 5

FIG. 1

FIG. 6

Fig. 1 is a perspective view of one of the end clamp members of the double-clip clothes pin of my design with the connecting cross bar broken away for drawing simplicity;

Fig. 2 is a front elevational view of the complete double-clip clothes pin of my design;

Fig. 3 is a rear elevational view;

Fig. 4 is a top plan view;

Fig. 5 is a bottom plan view; and

Fig. 6 is a left end elevational view.

I claim:

The ornamental design for a double-clip clothes pin, substantially as shown and described.
